UNITED STATES PATENT OFFICE.

EMILE GÉRARD DE FESTENBURG AND ARTHUR GÉRARD DE FESTENBURG, OF NEW YORK, N. Y.

ROLLER BALL SKATE.

Application filed February 4, 1926. Serial No. 85,899.

The invention relates to improvements in rolling ball skates and has for its object to provide a novel form of rotatable members in which the bearing is made upon the surface of the said members instead of at the axis thereof as is ordinarily the case.

A further object is a frame adapted to be supported on the said rotatable members and having cushioned extremities which may be used as a means for propulsion, or retardation as required.

The skate is further provided with means of attachment for the roller casings of such form as to permit of the rivet heads being below the surface of the foot plate.

These and other objects will be more clearly described in the following specification and illustrated in the drawings, in which:

Fig. 1 shows a top view of the skate with the locations of the rollers indicated thereon.

Fig. 2 shows a vertical section on the line 2—2 of Fig. 1.

Fig. 3 shows a vertical cross section on the line 3—3 of Fig. 1.

Fig. 4 shows an enlarged section of a bearing casing and detail of manner of attachment to the skate frame.

Fig. 5 shows a fragmentary view of the toe of the skate with portion of shoe thereon.

Fig. 6 shows another form of bearing casing.

Fig. 7 shows a form of the invention in which the roller members are placed in line front and rear, and the skate frames designed for the right and left foot respectively.

The component parts of the device are as follows:

A frame 10 having side members as shown at 11, toe clamps as shown at 12, and heel retainer 13; is provided with recessed members as shown at 14, 15 etc., to which are secured the bearing casings as shown at 16 and 17 by means of the sockets as shown at 18 and the rivets 19. Steel balls of varying sizes as shown at 20, 21, etc., rest within the said bearing casing and are retained by means of the shoulders as shown at 22. Resting within the casing above described are rolling members of spherical form as shown at 23.

It is obvious that this construction reduces friction to a minimum in the bearing, and

presents continually new bearing surfaces, 55 thus providing great wearing capacity.

The sides of the frame 10 are inclined inward as shown at 24 and 25 to provide greater clearance from the floor, or pavement when the user inclines to the right, or left. 60 A bottom plate 26 is perforated as required to receive the bearing casings as shown.

Cushion members as shown at 27 and 28 are secured to the frame 10 at the toe and heel thereof and provide means for propulsion when the foot is inclined so as to bring one of the said cushions in contact with the pavement. Retardation may be obtained in a similar manner; preferably 65 using the heel cushion.

The heel retainer 13 is provided with suitable straps and buckles and also with a metal reinforcement as shown at 29. A slot 30, serves to hold a toe strap when desired. Additional perforations as shown at 31 and 32 are provided to permit of shifting the 70 position of the rear roller when desired.

In the form of bearing casing shown in Fig. 6 of the drawings; the balls are all of one size and are retained by the curved 80 rim 33.

In the skate as illustrated in Fig. 7; the frames 10 are shaped for the right and left foot respectively and the roller members are placed in line from front to rear; the general 85 construction is as before shown.

The device as illustrated and described herewith, not only presents a new and novel form of construction, but permits, when in use, of movements which are not 90 possible with roller skates of conventional design.

While we have above described the preferred form, construction and arrangement of the several elements employed, it will be 95 understood that the device is, nevertheless, susceptible of considerable modification therein, and we therefore reserve the privilege of resorting to all such changes as may be fairly embodied within the spirit and 100 scope of the invention as claimed.

Having thus described our invention, what we claim as new and desire to secure by Letters Patent, is as follows:

1. In a rolling ball skate, a frame, downward and inwardly inclined side members thereon, bearing casings secured to the said frame, a plurality of balls in the said cas-

ings and spherical rotating members resting against the said balls and means to retain the said balls in position, cushion members secured to the forward and rear extremities of the said frame, and means to attach the whole to a shoe or like article.

2. In a rolling ball skate, a frame having downturned sides and with recessed portions in the face of the said frame, and secured thereto by means of socket members and rivets, bearing cases having therein a plurality of balls of varying sizes, and resting

against the said balls and retained within the said casing, spherical rotating members, cushions on the front and the rear extremities of the said frame and means to change the position of one rotatable member to another location on the said frame, clamps and straps for the attachment of the device to a shoe.

In testimony whereof we have affixed our signatures.

EMILE GÉRARD de FESTENBURG.
ARTHUR GÉRARD de FESTENBURG.
